UNITED STATES PATENT OFFICE

2,571,861

WOOD SURFACING AND EDGING MACHINE

Van J. Gegumis, Memphis, Tenn.

Application November 26, 1948, Serial No. 62,058

4 Claims. (Cl. 144—36)

1

This invention relates to woodworking machines of the type which employ rotary cutter heads for respectively dressing the surfaces and edges of boards or other strip-like timbers, and for shaping the cross sections of such surfaces or edges.

It particularly relates to machines which coordinate the actions of these heads into cooperative coacting relation.

The objects of the invention are:

To effect this coordination whereby to accomplish in a single operation results heretofore accomplished in multiple operations; and

To provide means coordinating in a single mechanism a plurality of closely related operations:

To provide edger means which are relatively adjustable laterally to determine the board width; and individually are vertically adjustable to vary the cutting height and inclinable with reference to the vertical to vary the inclination of the edge cut or to insure accuracy of the angular relation of the board edge to the board surface:

To provide means for driving the edger heads and maintaining unchanged relative relation between the heads and the driving means therefor:

To provide surfacing means including upper and lower cutter heads and means for adjusting the upper and lower cutter heads in conformity with the desired thickness of the board, and driving means for each thereof; and means for maintaining the driving relation between each said cutter head and its related driving means irrespective of the adjustment of said related head:

To provide feeder means; means for driving said feeder means; means for relatively adjusting said feeder; means to conform to variations of board thickness; and means for adjusting the feeding alignment of said feeder means with reference to the work supporting table and cutting means of the machine to insure desired longitudinal direction of board movement along the table.

The means by which the foregoing and other objects are accomplished, and the manner of their accomplishment, will readily be understood from the following specification on reference to the accompanying drawings, in which:

Fig. 1 is a front elevational view of the machine.

Fig. 2 is the related plan view.

Figs. 3 and 4 are corresponding views of the opposite ends of the machine.

Fig. 5 is a somewhat enlarged sectional elevational view of one of the edger heads and shaft mountings taken on the line V—V of Fig. 6.

2

Fig. 6 a sectional plan view taken on the line VI—VI of Fig. 1.

Fig. 7 is the rear elevation view of the machine.

Fig. 8 is a fragmentary sectional elevation taken on the line VIII—VIII of Fig. 7 showing means for adjusting the mountings of the motors driving the surfacing heads.

Fig. 9 is a fragmentary detail taken in the direction of the arrow IX (Fig. 5) showing the angularly shiftable attachment of the edger head shaft mounting, to its carrier slide.

Fig. 10 is a fragmentary enlarged sectional elevational view of the lower surfacing head and adjacent table portions taken on the line X—X of Fig. 2.

Fig. 11 is a fragmentary sectional plan view taken on the line XI—XI of Fig. 10; and

Fig. 12 is an enlarged fragmentary sectional elevational view taken on the line XII—XII of Fig. 2 showing feed roll alignment adjusting means.

Referring now to the drawing in which the various parts are indicated by numerals:

The machine comprises a supporting frame 25 which may, for convenience in manufacture or otherwise, include lower and upper portions. The lower portion comprises a frame having front legs 12 and 14 and rear legs 16 and 18 disposed in a rectangular pattern. The front and rear legs 12 and 16 at one end are joined by a transverse base member 20 and a transverse cap member or cap 22, and the legs 14 and 18 at the opposite end by transverse base and cap members 24 and 26. Longitudinal base members 28 join the posts and transverse base members 20, 24.

The upper portion of the frame essentially comprises transverse end members or ends 30 and 32 which are respectively seated on and secured to the caps 22 and 26 and are interconnected by a zigzag flanged member or rib 34 which includes a transverse portion 34A, the ends and rib being topped by a work supporting table 36.

Mounted by the upper portion of the frame are oppositely disposed edger heads mounted on upright axes which are laterally and vertically shiftable, and angularly tiltable in the respective transverse planes of their axes. The constructions include longitudinally offset brackets 38 and 40 which are secured to and extend horizontally away from the rear and front sides respectively of the rib member 34 and respectively include dovetail races 38A, 40A, mounting complementary slides 42 and 44 which are adjustably shifted forwardly and rearwardly by screws 46 and 48. Mounted on the slides 42 and 44 are brackets 50, 52 which respectively include disc

portions seated against the slides, and annular portions 50A, 52A, slotted along one side and provided with ear portions 50B, 52B similarly spaced, and with clamping belts 50C, 52C. The disc portion of each barrel is turnably centered by a pin 53 (Fig. 5) and has arcuate slots 54 through which cap screws 54A extend into the slide 44 (Fig. 9). The screws 54A are loosened to allow disc shift and permit the axis of the barrel to be angularly inclined from the vertical in a plane transverse to the machine and thereafter are reclamped. Angular adjustment may be accomplished by a screw 54B which is threaded through a swiveling nut 54C carried by a bracket 54D attached to the slide 44. The screw 54B is 15 rotatably secured in a socket 54E pivotally attached to the barrel 52A.

Clamped in the annular bracket portions 50A, 52A are substantially identical cylindrical barrels 55, which extend thereabove and therebelow. Each of these barrels (Fig. 5) has secured thereto a lug 55A which is internally threaded to receive an adjusting screw 56 through which the barrel is raised and lowered. An abutment 58 is anchored between the ear portions 52B and secured by a screw 60, the abutment journaling the screw 56 against longitudinal movement.

Shafts 62 are respectively journalled in each of the barrels 55 by bearings 64 which have their outer races seated against opposite outwardly faced annular internal shoulders in the barrel. The inner races of the bearings are spaced apart by a sleeve 66, and are confined between a shoulder 62A adjacent the upper end of the shaft and a nut 62B adjacent its lower end. Above the shoulder 62A the shaft carries an edger head 67, and below the nut 62B a driving pulley 68 preferably of grooved type.

Clamped around the barrel above and below the bracket 52 are encircling brackets 70 having hub portions 70A from which arms 72 project laterally. The arms 72 are rigidly secured to and support the base 74 of an electric motor 76 which mounts and drives a pulley 78 and through a belt 80 drives the pulley 68, shaft 62 and edger head 67.

The above description defines a construction in which the edger head and driving motor as a unit, are adjustable without relative displacement the one to the other, toward or away from the work, and vertically and at an angle inclined to the vertical. The other barrel 55 mounts a similar assembly including an edger head 82 and motor 84 and establishes a similar unit.

Mounted on the end 30 of the frame is a vertically disposed dovetail slideway 90 in which is mounted a complementary slide portion of a bracket 92. The bracket is raised and lowered by a screw 96. Mounted on the upper end of the bracket is a transversely disposed split housing 98 in which is mounted a barrel 100. The barrel is laterally shiftable by a screw 102 and clamped, except during shift, by screws 104. Journalled in the barrel is a horizontally disposed shaft 106 which extends into underlying relation with the table 36 and carries a surfacing head 107, the housing, barrel, and shaft construction preferably being substantially similar to that shown in Fig. 5 except that the barrel does not mount the related motor. The shaft 106 is driven by a motor 108 through a belt 109 and suitable pulleys. The motor 108 is mounted on a plate 110 which is hingedly supported at one side by a rod 111 and at the opposite side by standing studs 112 and adjustable nuts 112A. The studs 112 are secured

5 to and extend upward from the base members 28 of the machine frame. The motor is raised or lowered by adjustment of the nuts, to compensate for similar raising and lowering of the shaft 106 and cutter head 107 carried thereby. If desired a steady member 114 may be secured to the housing, and therebeyond be offset to pass the head 107 and extended radially inward to journal the outer end of the shaft 106.

Overlying the table 36, is a complementary surfacing head 116 which is mounted on a shaft 118 and driven through suitable pulleys and belts 119 by a motor 120 mounted on a plate 110A which is adjustable with relation to the base 28 in similar manner to the plate 110. The shaft 118 is journalled in a housing assembly 121 and includes a vertically disposed slideway 122 secured to the transverse portion 34A of the zigzag rib 34 and a cooperating slide carried bracket 123 which is raised and lowered by a screw 124 and is substantially the same as the above described assembly carried by the housing 98. The assembly may also include an outboard bearing 126 for the shaft.

25 The lumber is preferably fed to the cutter heads by two pairs of corrugated rolls 128, 130 each pair comprising an upper and a lower roll. The rolls are driven at concurrent speeds, preferably by a motor 132 through a gear reduction unit 133 which through a chain 134 drives a countershaft 135. The countershaft, through a chain 136 drives the two lower rolls and through a chain 137 drives the two upper rolls. An idler sprocket 138 bears against the chain 137 and is adjusted by a screw 139, through an interposed spring 140. The two lower rolls are mounted on shafts 141 which are journalled in a cradle 142, this cradle being vertically slidable between an upright member 144 forming a part of the end frame 32 and a second member 146 secured to the end frame, and being guided by such members. A screw 148 provides means for raising and lowering the cradle and rolls to adjust the roll level with respect to the table surface.

40 The upper rolls are mounted on shafts 150 which are journalled in housings 152. The housings are carried by arms 154 which jointly pivot on a stud 156 which projects horizontally from a vertically disposed slide 169. The slide is supported and guided for vertical movement, by a 45 complementary slideway portion of a bracket 158. The bracket has a base portion or base 158A, seated on the table 36 and secured thereto by cap screws 159, 159A, the latter of which (Fig. 12) passes through a slot 158B in the base, and when 50 loosened allows a minor shift of the base about the cap screw 159 as a pivot, and permits a micrometric shift in alignment of the rolls 128 carried by the shafts 150. Shift of the base 158A is preferably accomplished by a screw 161 turnably mounted in an abutment 161A secured to the table 36, the screw being threaded into one side of the base 158A. The slide 160 is linked to the bearing housings 152 through bolts 162. Interposed between the carrier and the housings are 55 compression springs 164, the tension of which may be adjusted by nuts 166. Spacing of the upper rolls from the lower rolls, is adjusted by a screw 168 which raises or lowers the slide 160.

60 Mounted on the end frame 30 remote from the feed rolls and below the surfacing head 107 is a bracket 170, having arms 170A which project beyond the head 107 and carry rigidly secured upwardly extending braces 172 and in adjacency thereto are apertured to receive a bolt 174. The 65 bolt 174 removably supports a vertical plate 176

which is additionally secured in such upright position by screws 178 which are tapped into the braces 172. Secured to the plate 176 are spaced guideways 180 which slidably engage the opposite edges of the vertical leg 182 of an angle bracket. The lower end of the leg 182 has an extending flange 182A through which is threaded an adjusting screw 184. The screw 184 is turnably journaled in an abutment 186 rigidly secured to the plate 176.

Extending from the upper end of the angle leg 182 is the horizontal leg 188 of the angle member. The leg 188 mounts an auxiliary table 190 which has the general level of the table 36 but which may be raised above or lowered below that table by the screw 184. The underside of the table 190 and upperside of the horizontal leg are provided with complementary keyways 190A and 188A respectively parallel to the longitudinal axis of the table 36 in which is disposed a key 192, which allow the table 190 to be shifted toward or away from the surfacing head 107. The leg 188 is also provided with slots 188B laterally disposed in parallelism with the keyways through which clamping screws 194 engage the overlying table 190. Mounted on the table 190 are longitudinally disposed guides 196 of angle cross section which are adjustably clamped to the table by bolts 198 which pass through laterally disposed slots 188C in the table 190. The table is adjusted by leveling screws 199.

The table 36, also, is preferably provided with adjustable extensions 200, which are countersunk to table level and are longitudinally slotted to receive clamping screws 202.

In use the lower feed rolls 128, are adjusted by the screw 148 relatively to the level of the table 36, and the upper rolls 130 are spaced from the rolls 128, to conform to the thickness of lumber to be surfaced, by the screw 168.

The lower surfacing head 107 is adjusted through the screw 96 to proper level with regard to the table and the upper surfacing head 116 adjusted through the screw 124 as required to cut the desired thickness of finished lumber. To conform to these adjustments the plates 110 and 110A are raised or lowered by the screws 112 to maintain proper spacing of the motors 108 and 120 from their related surfacing heads 107 and 116.

The edger heads, 67 and 82 are vertically adjusted by shift of the barrels 55, as through the screw 56 (Fig. 5), and if desired inclined to bevel the lumber edges, by loosening the screws 54A (Fig. 6) and turnably shifting the plate 52, and the related barrel 55, with reference to the slide 44.

The width of the lumber edged, is determined by shift of the slides 42 and 44 relatively to the brackets 38 and 40, by the screws 46 and 48, and shift with these slides of the barrels 56 carried thereby and the edger heads journaled by the barrels.

This shift of the barrels effects a concurrent shift of the motors, 76 and 84 which are rigidly supported by the barrels and maintains the driving relations of the motors to the edger head shafts.

As the lumber is fed through by the rolls 128, 130 toward the edgers, its longitudinal alinement may be adjusted by shifting the upper rolls 130 through the adjusting screw 161.

It will be understood that while the cutter heads are shown with straight knives attached to established cylindrical heads, the knives may

have such other patterns either well known or otherwise as may be desired and that their configuration forms no part of the present invention.

It will be further understood that much of the detail shown is illustrative only and that I do not wish, or intend to limit myself to such detail except where in any claim it may be set out.

I claim:

1. A woodworking machine including a frame carried work supporting table and means for feeding lumber longitudinally along said table, said table having intermediate its width a vertically depending rib including forward and rearward, laterally offset longitudinally extending portions and an interconnecting portion, said forward rib portion being adjacent one side of said table and said rearward portion lying inward therefrom, brackets respectively secured to the inner side of said forward portion and the outer side of said rearward portion, and extending laterally and horizontally away therefrom, said brackets each including a guideway, and edger units carried by said brackets, said units each including a slide carried by said guideway and means for adjusting said slide toward and away from said table, a shaft carried cutterhead having an upright axis, a barrel carried by said slide and journaling said shaft, a motor axially aligned with and operably coupled to said shaft, means extending between said barrel and said motor rigidly joining said barrel and said motor as a unit, means for axially adjusting said barrel with respect to said slide and said table, and means for inclining said barrel in the plane of its axis transverse to said table.

2. A woodworking machine including a frame carried work supporting table and means for feeding lumber longitudinally along said table, said table having intermediate its width a vertically depending rib including longitudinally spaced, laterally offset, longitudinally extending portions and an interconnecting portion, a first of said longitudinal rib portions being adjacent one side of said table and the second thereof lying inward from said first portion, brackets respectively secured to the inner side of said first portion and the outer side of said second portion, and extending laterally and horizontally away therefrom, and edger units carried by said brackets, said units each including a shaft carried cutterhead having an upright axis, and a motor axially aligned with and operably coupled to said shaft; means for vertically adjusting said shafts, means for inclining said shafts in the plane of their axes transverse to said table and means for adjusting said shafts toward and away from said table.

3. A woodworking machine including a frame carried work supporting table and means for feeding lumber longitudinally along said table, said table having intermediate its width a vertically depending rib including longitudinally spaced, laterally offset, longitudinally extending portions and an interconnecting portion, a first of said longitudinal portion being adjacent one side of said table and the second thereof lying inward from said first portion, a bracket secured to the inner side of said first portion and extending laterally and horizontally away therefrom, and an edger unit carried by said bracket, said unit including a shaft carried cutterhead having an upright axis, and a motor axially aligned with and operably coupled to said shaft; means for vertically adjusting said shaft, means for inclining said shaft in the plane of its axis

transverse to said table, and means for adjusting said shaft toward and away from said table.

4. A woodworking machine including a frame carried work supporting table and means for feeding lumber longitudinally along said table, said table having intermediate its width a vertically depending rib including longitudinally spaced, laterally offset, longitudinally extending portions and an interconnecting portion, a first of said longitudinal portions being adjacent one side of said table and the second thereof lying inward from said first portion, a bracket secured to the outer side of said second portion, and extending laterally and horizontally away therefrom, an edger unit carried by said bracket, said unit including a shaft carried cutterhead having an upright axis, and a motor axially aligned with

and operably coupled to said shaft; means for vertically adjusting said shaft, means for inclining said shaft in the plane of its axis transverse to said table and means for adjusting said shaft toward and away from said table.
